CLAIM

We claim the ornamental design for a digital audio disc player for an automobile, as shown and described.

DESCRIPTION

FIG. 1 is a top perspective view of a digital audio disc player for an automobile of the present invention;

FIG. 2 is a front view thereof;

FIG. 3 is a first side view thereof;

FIG. 4 is a top view thereof;

FIG. 5 is a bottom view thereof; and,

FIG. 6 is a second side view thereof.

The rear view has been omitted and forms no part of the claimed design.
